UNITED STATES PATENT OFFICE.

WALTER H. COOK, OF NEW ORLEANS, LOUISIANA.

PERCOLATING COFFEE-POT.

1,112,598.

Specification of Letters Patent.

Patented Oct. 6, 1914.

Application filed May 28, 1912. Serial No. 700,267.

To all whom it may concern:

Be it known that I, WALTER H. COOK, a citizen of the United States, residing at New Orleans, in the parish of Orleans and State of Louisiana, have invented new and useful Improvements in Percolating Coffee-Pots, of which the following is a specification.

This invention relates to improvements in percolating coffee pots, and its objects are to enable the drip of the infusion into the boiling chamber to be accurately regulated at any desired degree, and at the same time, to enable a complete dissociation of the parts in the percolating chamber for cleaning or other purposes.

An embodiment of the invention is illustrated in the accompanying drawings, wherein:

Figure 1 is a vertical central sectional view of the coffee pot in which the features of the invention are incorporated; Fig. 2 is a plan view of the percolating chamber. Fig. 3 is a perspective view showing a detail of construction.

Similar characters of reference designate corresponding parts throughout the several views.

The coffee pot comprises a boiling chamber 1 and a percolating chamber 2. The latter may be of any well known form. As shown, it is in the form of a sheet metal cylinder, and is formed with a slightly reduced extension 3 which projects into an opening in the top of the chamber 1, and defines a shoulder 4 whereby the chamber 2 is supported upon the chamber 1.

The extension 3 has a conical bottom which is formed with an opening 5 of suitable diameter, and through which the infusion drips from the chamber 2 to the chamber 1. The effective size of the opening 5 is controlled by a needle valve 6, which passes axially through the chamber 2 and at its upper end projects beyond said chamber.

The support for the valve 6 includes a tube 7 which is arranged within the chamber 2 in surrounding relation to said valve, and which has fixed at its end a perforated screening plate 8 to prevent any grounds

from passing over into the chamber 1. The tube 7 projects at its upper end beyond the chamber 2, and its upper edge is formed with a series of steps 9 of successively increasing height. The valve 6, at its upper end, is provided with a laterally projecting pin 10 which is adapted to rest upon any one

of the steps 9. It will be obvious that the position of the valve 6 with reference to the opening 5 depends upon which particular step 9 of the tube 7 is engaged by the pin 10. If the lower step 9 is engaged by said pin, the opening 5 is of its smallest effective size. If higher steps 9 are engaged by the pin 10, the effective size of the opening 5 is correspondingly increased.

The chamber 2 is closed by a flanged cover 11, the upper face of which contains designations to indicate the strength of the coffee which will be produced in any particular position of the valve 7, and these designations correspond in arrangement and number to the arrangement and number of the steps 9, which are arranged above said cover, the latter having a central opening 16 through which the tube 7 projects. Thus, the designations on the cover 11 may comprise the words "Light," "Medium," and "Dark." The word "Light" is arranged adjacent the highest step 9; the word "Medium" is arranged adjacent the intermediate step 9; and the word "Dark" is arranged adjacent the lowest step 9. If the finger 10 points to the word "Dark," as shown, said finger is resting on the lowest step 9, and an indication is thereby given that full strength coffee will be produced. In like manner, if the finger 10 points to the words "Medium" or "Light," said finger rests upon the step adjacent said words, and an indication is given that coffee will be produced of medium or least strength, as the case may be.

In order to insure of the accuracy of the readings above referred to, the cover 11 should always occupy a definite position, and for this purpose, said cover may have its edge provided with a notch 12, and the upper edge of the chamber 2 may be provided with a pin 13, which will project into the notch 12 and thereby hold the cover in the definite position referred to, and prevent any movement of the cover from said position. In this way, the accuracy of the readings and of the adjustment of the valve 6 is assured.

If desired, a perforated plate 14 may be arranged in the chamber 2, above the coffee, the water being poured through this plate, which thereby uniformly distributes the water over the coffee in said chamber. The plate 14 loosely surrounds the tube 7 and may rest upon an annular bead 15.

It will be observed that the cover 11 may

be removed whenever necessary, without interfering with the arrangement or relation of the valve 16, and that said valve is entirely dissociable from the tube 7. Or, if desired, the tube 7 and the valve 6 may be withdrawn in a unitary manner from the chamber 2, to enable complete access to all the parts for cleaning or other purposes.

Having fully described my invention, I 10 claim:

1. In a coffee pot, a boiling chamber, a percolating chamber communicating therewith, a tube projecting beyond the percolating chamber and having a stepped upper 15 end, a needle valve to control the drip of coffee from the percolating chamber to the boiling chamber, the valve having a laterally projecting pin to engage upon the stepped upper end of the tube, a cover for 20 the percolating chamber, the cover having an opening through which the tube projects and having designations corresponding to the steps upon the upper end of the tube and means for holding the cover when closed 25 upon the percolating chamber in a definite position with relation to said tube.
2. In a coffee pot, a boiling chamber, a percolating chamber communicating therewith, a tube projecting beyond the percolating 30 chamber and having a stepped upper end, a needle valve to control the drip of coffee from the percolating chamber to the boiling chamber, the valve having a laterally projecting pin to engage upon the 35 stepped upper end of the tube, and a perforated plate provided upon the lower end of the tube and supported upon the bottom

of the percolating chamber, the plate in turn supporting the tube.

3. In a coffee pot, a boiling chamber, a 40 percolating chamber communicating therewith, a tube projecting beyond the percolating chamber and having a stepped upper end, a needle valve to control the drip of coffee from the percolating chamber to the 45 boiling chamber, the valve having a laterally projecting pin to engage upon the stepped upper end of the tube, and a removable cover closing the upper end of the percolating chamber and provided with an 50 opening through which the tube projects.

4. In a coffee pot, a boiling chamber, a percolating chamber having an opening in its bottom communicating with the boiling chamber, a removable cover for the percolating chamber, a valve extending vertically through said percolating chamber and formed to regulate the effective size of said opening, a tube inclosing the valve, the upper ends of the valve and the tube projecting through the cover and the valve being supported by the tube and being adjustable lengthwise thereof, and a perforated screening plate for straining the infusion passing to said opening, said plate being 65 removably supported within the percolating chamber and rigidly secured to the tube.

In testimony whereof I have hereunto set my hand in presence of two subscribing witnesses.

WALTER H. COOK.
